UNITED STATES PATENT OFFICE.

THOMAS WHYTE GUTHRIE, OF SOUTHPORT, ENGLAND, AND CRERAR GUTHRIE, OF YOKER, GLASGOW, SCOTLAND.

BILLIARD-CUE TIP.

Application filed October 22, 1927, Serial No. 228,068, and in Great Britain November 12, 1926.

This invention of an improved billiard cue tip comprises and is made up of six different parts, namely 1st tip, 2nd leather washer, 3rd felt washer, 4th thimble, 5th holder and 6th holder screw. In the accompanying drawings, Fig. 1 shows a section and Fig. 2 an elevation of the cue and tip. The thimble 4 and holder 5 consists of two tubes each having an inward turned flange to hold tip 1 while the bottom end of the holder is screwed inside so as to be screwed on to holder screw 6. The tip 1 leather washer 2 and felt washer 3 are inserted into the thimble 4 and pushed up until the shoulder of the tip is pressed against the top inward flange of the thimble. The thimble is then placed on to the tip-end of cue which is turned down to fit the inside of the thimble. The holder 5 is slipped over the thimble and screwed down to the holder screw 6 which is fixed on the turned end of the cue.

We claim:

1. In a billiard cue, a tip, a shoulder on

said tip, an inner tube, an outer tube embracing the inner tube, flanges on both tubes engaging the shoulder on the tip, means for cushioning the tip against the end of the cue, and means for fixing the outer tube with the cue in such manner as to draw the tip against the end of the cue with the cushioning means between for fastening the tip to the cue.

2. In a billiard cue a tip, a shoulder on said tip, a reduced end to the cue, an inner tube embracing said reduced end, an outer tube embracing said inner tube, inturned flanges on both tubes engaging said shoulder, resilient washers for cushioning the tip against the end of the cue, a screw thread carried by the cue, a co-acting thread on the outer tube for drawing the tip towards the end of the cue and fastening the said tip to the cue.
